(57) **CLAIM**

The ornamental design for a golf club wrench, as shown and described.

DESCRIPTION

FIG. 1 is a front perspective view of an embodiment of a golf club wrench in accordance with our new design.

FIG. 2 is a front elevational view of the golf club wrench of FIG. 1.

FIG. 3 is a side elevational view of the golf club wrench of FIG. 1.

FIG. 4 is a top plan view of the golf club wrench of FIG. 1; and,

FIG. 5 is a bottom plan view of the golf club wrench of FIG. 1.

The broken line showing is for illustrative purposes only and forms no part of the claimed design.
